UNITED STATES PATENT OFFICE.

JACOB B. YEAGLEY, OF INDIANAPOLIS, INDIANA.

SASH-HOLDER.

SPECIFICATION forming part of Letters Patent No. 226,147, dated March 30, 1880.
Application filed September 6, 1879.

To all whom it may concern:

Be it known that I, JACOB B. YEAGLEY, of Indianapolis, in the county of Marion and State of Indiana, have invented certain new and useful Improvements in Sash-Locks; and I do hereby declare the following to be a full, clear, and exact description thereof, reference being made to the accompanying drawings, forming a part of this specification, and in which—

10 Figure 1 represents my improved locks set into the window-frame for engaging with the upper and lower sashes, showing a vertical section of the lock for engaging with the upper sash and a side view of the lock engaging 15 with the lower sash. Figs. 2 and 3 are detail views in the construction of the escutcheon-plates and keys to be used in connection with my improved locks.

This invention relates to certain new and 20 useful improvements on my former patents for combined sash holders and locks, numbered and dated, respectively, 205,517, July 2, 1878, and 218,612, August 12, 1879, and more especially to improvements on the lock portions 25 thereof, having for its object the production of a sash-lock more especially adapted for sashes provided with balances, such as weights, springs, &c., in contradistinction to my former 30 patents above referred to, and which were particularly adapted for sashes having no balances.

The invention also relates to certain new and useful improvements in escutcheon-plates and keys especially designed and adapted for 35 my improved sash-locks and combined sash holders and locks; and to this end the invention consists in the general construction and combination of parts, all as will be hereinafter fully described, and specifically set forth in the 40 claims.

To enable others skilled in the art to which my invention is most nearly connected to make and use the same, I will now proceed to describe the construction and operation of the 45 several parts.

In the drawings, A A' represent the two side case-plates, provided with journal-bearings for the check-shank B and dovetailed 50 projections fitting into a recessed shoulder, e, in the face-plate C, said parts being secured together by rivets, all as clearly set forth and

covered by my former patent, dated August 12, 1879, before referred to.

The face-plate C in the present case is reduced to nearly one-half the length used in the 55 combined sash holder and lock, and one of the projecting portions of the tumbler D is dispensed with on account of dispensing with one of the check-shanks necessary in the combined sash holder and lock.

In my present construction of sash-lock a third case-plate, A², is essential for closing the end opening between the two side case-plates, A A', and which may be cast or formed with the face-plate C, as clearly shown in Fig. 1, or 65 made in a single piece with either of the side case-plates, or one-half of said plate A² made 60 on each of the side case-plates.

While I do not wish to be confined to any particular arrangement of the case-plate A², 70 still I prefer to cast or form it with the face-plate C, for if made with the side case-plates there would have to be rights and lefts, thus necessitating their being sorted out in manufacturing or putting of the lock together, consuming much time, which the present arrangement obviates, while facilitating the manufacture of the locks.

The face-plate C is provided on its inner face, near one end thereof, with a cross-bar, e, and 80 a recess, e', for the purpose of securing one end of a flat steel spring, E, in place, the other end of said spring resting and working on the heel of the check-shank B. This is a much better arrangement than the spiral springs 85 used in my former patents above referred to, as it is more durable and reliable. This cross-bar e is a very essential feature, as while holding the spring firmly in position it forms a solid rest for the lock when adjusted in the 90 mortise of the window sash or frame, (the present construction of lock permitting of its being applied either in the window-frame or the sashes, as may be deemed expedient,) and also by the use of the cross-bar e and the 95 spring E, as arranged, the check shank or shanks cannot be drawn out of the face-plate, as is the case in my former patents.

The tumbler D is cut away at d, adjacent to check-shank, so as to permit said check-shank to come down farther, thus giving it the requisite play necessary in locking or unlocking it.

The portion *b* of the check-shank at the heel thereof forms a back-stop for the tumbler *D*, while a shoulder, *b'*, on the inside of the end case-plate, *A*², forms a forward stop for said tumbler. Consequently, to unlock the check-shank, the key must be turned to the left for lock of lower sash and to the right for lock of upper sash.

As before stated, my improved sash-lock is only adapted for sashes having balances, and to apply it, raise the lower sash as high as it can be raised, then put lock in mortise formed in window-frame, with the short end of face-plate upward, when the sash can be drawn down to any desired point and balanced by weights or springs in the usual manner, but cannot be raised without unlocking or throwing back the check-shank through the medium of the tumbler and key.

For the upper sash the lock is placed in mortise in window-frame in a similar manner, with the short end of face-plate, however, reversed or downward. In fact, for the upper sash my improved lock acts as both a sash holder and lock—as, for instance, if the upper sash were opened by being let downward for ventilation it could not be pushed farther down, and consequently it prevents sash from going down without unlocking the check-shank.

With key, but could only be pushed up without the use of the key, which would only be closing the window, and which, when closed, could only be put down by unlocking check-shank. This lock, it will also be observed, is particularly convenient in case of storms coming up quickly—as, for instance, if both sashes were sufficiently opened for ventilation, and in the event of a storm coming up quickly or suddenly the upper sash could be pushed up or closed and lower sash down or closed without resorting to the use of the keys, and when closed would be instantly locked by the automatic action of the check-shank.

My improved lock also possesses the advantage over my sash holders and locks of being adapted to be applied to either the window frame or sashes, and also costing about one-third less in the manufacture.

When deemed expedient, a rubber or serrated metal strip might be set in the sash or in the window-frame for the check-shank to work against.

H represents an escutcheon-plate to be set

in the side of the window-frame, through which the key *I* passes for operating the tumbler *D* 55 in unlocking the check-shank. This plate *H* is provided on its inner face with lugs *h h*, directly opposite each other, and against which the projection *i* will strike and prevent the key from turning entirely around, thus preventing the tumbler from being turned over and over, as is the case in my former patents above referred to.

The escutcheon-plate *H* can also be made concave, as shown in Fig. 4, and set in the 65 window-frame, for the reception of the cylindrical-headed key *I*, which can always be left in lock, and which can be turned by another key, *g'*, fitting in a square opening, *j*, in the cylindrical head of the key. This is very essential in case of inside window-blinds, as it prevents the blinds from striking or breaking the thumb-piece of the keys, and consequently avoids defacing of the blinds.

Having thus fully described my invention, 75 I do not desire to be understood as claiming, broadly, a sash-lock having pivoted and spring cam levers or arms operated by a key, nor, broadly, anything shown and claimed in my former patents.

I am aware that flat springs applied in a similar manner to hinges are old, and such I distinctly disclaim as my invention; but

I claim—

1. In a sash-lock, the combination, with the 85 pivoted check-shank *B*, face-plate *C*, and side case-plates, *A A'*, of the tumbler *D*, cut away at *d*, and the horizontal end case-plate, *A*², with its stop *b'*, substantially in the manner as and for the purpose herein shown and described.

2. In a sash-lock, the combination, with the tumbler *D*, of the check-shank *B*, provided with the stop *b*, and the end case-plate, *A*², provided with the stop *b'*, substantially as and for the purpose herein shown and described. 90

3. In a sash lock or holder, the combination, with the pivoted check-shank, tumbler, and key, of the face-plate *C*, provided with the cross-bar *e* and recess *e'*, and the flat steel spring *E*, substantially as and for the purposes herein shown and described. 95

JACOB B. YEAGLEY.
